UNITED STATES PATENT OFFICE.

EDWIN J. ARMSTRONG, OF ERIE, PENNSYLVANIA, ASSIGNOR TO BALL ENGINE COMPANY, OF ERIE, PENNSYLVANIA, A CORPORATION OF PENNSYLVANIA.

PORTABLE ENGINE.

1,163,122.

Specification of Letters Patent.

Patented Dec. 7, 1915.

Application filed January 20, 1915. Serial No. 3,371.

To all whom it may concern:

Be it known that I, EDWIN J. ARMSTRONG, a citizen of the United States, residing at Erie, in the county of Erie and State of Pennsylvania, have invented new and useful Improvements in Portable Engines, of which the following is a specification.

This invention relates to portable engines and consists in certain improvements in the 10 construction thereof as will be hereinafter fully described and pointed out in the claims.

More particularly the invention is designed for use with steam shovels and the 15 invention is exemplified in connection with a steam shovel.

In the drawing illustrating the invention, 1 marks the frame, 2 the wheels, 3 the turn table, 4 the boom, 5 the hoisting engine and 20 6 the boiler. These are constructed in the ordinary manner.

The smoke box 7 is arranged on the top of the boiler. The flues 8 open through the head 9 of the boiler into the smoke box. 25 The smoke box is provided with the head 10 from which the stack 11 extends.

In the construction ordinarily used, the head 10 is secured to the smoke box and the stack 11 is hinged on the head so that it may be dropped down when the engine or shovel is being moved from one place to another. The ordinary mechanism of the steam shovel is somewhat lower than this, as for instance the point A on the boom braces. Furthermore, the small opening made by the stack does not expose the flues for cleaning. I obviate these difficulties by hinging the head 10 on the smoke box 7. A hinge bracket 12 is arranged at one side of the smoke box.

40 The hinge leaf 13 is fastened to the head 10 and the hinge pintle 14 completes the hinge. The hinge is secured in closed position by the bolts 15. A hook 16 is provided to which a chain may be attached for holding the head in an open position as shown in the upper dotted lines. With the head in this position, the flues may be cleaned. When it is desired to move the engine or shovel, the head may be thrown entirely 45 over bringing the stack alongside the smoke box and the boiler, thus reducing the height of the parts to the extent of the head and stack. In this way the length of the boiler may be increased and the capacity of the smoke box slightly increased without giving

undue height to the apparatus. By off-setting the hinge with relation to the stack 11 the stack is carried clear of the smoke box when it is swung back so that it may be dropped alongside of the boiler or smoke 60 box. In this way the diameter of the stack or head as increasing the height of the apparatus when being moved from place to place is obviated.

The roof 17 of the shovel is brought under 65 the overhanging portion of the cover 10. It is not feasible to make a very tight joint between the roof and the smoke box and this overhanging portion makes a closure against leakage. Carrying the smoke box up a distance to make this overhanging connection is made possible by reason of the fact that the added height incident to this construction of the cover does not form a permanent 70 obstruction along the top of the roof so as 75 to interfere with the free movement of the shovel where the clearance is close.

What I claim as new is:—

1. In a portable engine, the combination 80 of an upright boiler; a smoke box above the boiler; a head for the upper end of the smoke box hinged at the side of the smoke box; and a stack extending from the head.

2. In a portable engine, the combination 85 of an upright boiler having vertical flues extending therethrough; a smoke box above the boiler; a head for the upper end of the smoke box, said head being of a size to expose all the flues when in an open position, said head being hinged at the side of the 90 smoke box; and a stack extending from the head.

3. In a portable engine, the combination 95 of an upright boiler; a smoke box above the boiler; a head for the upper end of the smoke box; a stack extending from the head; and a hinged joint between the smoke box and the head off-set from the stack to permit the stack to be swung clear of the smoke box to a position alongside of the 100 smoke box.

4. In a portable engine, the combination 105 of an upright boiler having vertical flues extending therethrough; a smoke box above the boiler; a head for the upper end of the smoke box of sufficient size to expose all the flues of the boiler when the head is in open position; a hinged bracket on the smoke box extending outside the head; a hinge leaf on the head operating with the hinged bracket 110

to form a hinge connection between the head and the smoke box; and a stack extending from the head.

5. In a portable engine, the combination of an upright boiler; a housing for the boiler comprising a roof; a smoke box above the boiler extending through the roof; a head for the upper end of the smoke box hinged at the side of the smoke box and 10 overhanging the smoke box, protecting the

joint between the smoke box and the roof; and a stack extending from the head.

In testimony whereof I have hereunto set my hand in the presence of two subscribing witnesses.

EDWIN J. ARMSTRONG.
